UNITED STATES PATENT OFFICE.

WILLIAM P. SPRAGUE, OF SAN ANSELMO, CALIFORNIA.

NASAL DOUCHE.

Application filed December 19, 1922. Serial No. 607,825.

To all whom it may concern:

Be it known that I, WILLIAM P. SPRAGUE, a citizen of the United States, and a resident of San Anselmo, county of Marin, and State 5 of California, have invented a new and useful Nasal Douche, of which the following is a specification.

My invention relates in general to an apparatus for treating abnormal conditions of 10 the nasal cavity and other related anterior and posterior parts of the nasal passages.

The invention possesses many desirable features which are concerned not only with the valuable results realized by use of the 15 same but also in the convenience of manipulation, simplicity in construction, and other more or less mechanical characteristics. These features will clearly appear as the description proceeds with reference to the preferred embodiment of the invention as illustrated in the accompanying drawing, and in which Figure 1 is a perspective view illustrating the use of the douche, and Figure 2 is a view in vertical section of the major 20 parts of the device.

Referring now to the drawing in detail, I have discovered that diseases of the nasal 25 passages can be treated to the best advantage by a douche when the medicated liquid supply used is controlled or localized, so to speak, so as to avoid the possibilities of directing or otherwise supplying the liquid to the Eustachian tubes or any parts which would likely be impaired when subjected to the harsh action of the liquid with which 30 they are not intended to come in contact.

In practicing the treatment, I have elected to adopt an apparatus including a medicated liquid supply located at a lower plane than the patient's nasal orifices and which cannot 35 gravitate into the nasal cavity, with a communication between the same and one nostril of the patient's nose and means communicating with the other nostril of the patient's nose for creating a partial vacuum in the nasal cavity and in a receptacle in connection with said means for drawing a quantity of the medicated liquid supply up into one nostril through the nasal cavity and discharging it from the other nostril into said receptacle wherein the partial vacuum has 40 been created. By this method no liquid can enter the nose until a vacuum is produced in the nasal cavity, which differentiates it 45 from nasal douches hitherto invented. It

eliminates the ever present danger to the middle ear and mastoid region that obtains from the employment of douches that operate under direct pressure, and those where the liquid flows into one nostril under the influence of gravity alone. By my method negative pressure is first produced in the nasal cavity and in the above mentioned receptacle so that the stream takes the path of the least resistance through the nasal cavity under the suction force and flows into the receptacle as stated above. Unlike other douches, at the very beginning of the operation, and throughout the whole treatment, the stream is drawn away from the Eustachian tubes, sucking infectious material from their orifices, thereby preventing serious infection and often relieving the patient from catarrhal deafness. In this way the liquid is maintained under absolute control, 60 and it does not reach those parts that should not feel its contact. The vacuum in the nasal cavity and said means in connection with the drawing force exert strong influence in drawing infectious secretions from the nasal 65 sinuses and discharging them with the liquid through the nostril as previously mentioned.

So far as concerns the characteristic elements of the apparatus for carrying out the treatment, I would prefer to use a pair of receptacles, such for instance, as the glass bottles A and B. The same may be supported on a suitable base or the like C for convenience. The receptacle A provides the medicated liquid supply, and the neck of the bottle may be closed by a rubber or the like plug D, the same having a port or other opening E therein with the effected port area of the same controlled by a manually manipulated stopper F. Projecting through the stopper D and terminating just above the bottom of the bottle is a glass or the like tube G. The upper end of the tube terminates in an end H made to be connected to a more or less flexible tubing I which carries a nozzle like head J on its end. The other receptacle or bottle B is likewise made with the stopper D' and also equipped with a glass or the like tube G' which terminates short of the bottom of the bottle as in the case of the tube G, and protrudes through the stopper D' to receive the same kind of a tube I' as the tube I, and also including a nozzle-like head J'. The stopper D' is further provided with an opening E' into the bottle B with a 100

connection K connecting the bottle with the tubing L which carries the hollow, elastic bulb M on the end thereof.

In use a supply of medicated liquid is poured into the bottle A and the stoppers D, D' and F are fitted tightly into their respective places. Then the bulb M is compressed preferably by the elbow or arm as shown in Figure 1 so as to leave the hands of the patient free when the treatment is self-administered. This exhausts the air from bulb M. The nozzle like heads J and J' are then fitted to their respective nostrils and the patient breathes through his mouth and he then releases the bulb M from pressure and has free use of his hands and arms. Now the soft palate rises up in the pharynx and closes the nasal cavity from behind against the entrance of air through the mouth and, when all connections with the apparatus are tight, the elastic bulb M being released from pressure, expands slightly, sufficient to create a partial vacuum in bottle B, and the nasal cavity, and the patient feels the effect of suction in the nose. Then, as he loosens stopper F to permit the entrance of air above the surface of the liquid in bottle A, the elastic bulb M again expands and, with the aid of the air pressure upon the surface of the liquid in bottle A and the partial vacuum in bottle B and nasal cavity, and the resilience of the bulb M, the liquid flows upward out of bottle A into the nostril connected with the nozzle-like head J, where it passes through the nasal cavity and is discharged through the nostril communicating with the nozzle-like head J' into the bottle B.

If desired, after the liquid has been run through as described, the stopper F may be left out of or loose in its port E and, by compressing the bulb M, the liquid may be caused to flow back from bottle B through the nose into bottle A and, by alternate relaxation and compression, the liquid can be sent back and forth in either direction as may seem expedient. In other words, the douche can be operated without manipulating the stopper in its port, which is done for convenience and for regulating the rapidity or volume of the stream and the degree and duration of suction during the operation. The douche will operate without the stopper F but its use has advantages above cited. When the stopper F is not called into requisition the air bulb M expands the instant it is relieved from pressure, continuing so to expand until it is completely extended. Instead of manipulating the stopper F in its port E the end of a finger may be used or any means employed for regulating the amount of air pressure desired for operation. When the physician operates the douche for his patient he may control the air bulb M entirely with his hand

and, by so doing, he can get certain beneficial results in some cases where the ordinary methods of cleansing have failed to be efficient.

Another advantage in this form of nasal douche is that, after using it the liquid can be emptied from the bottles and the apparatus used in the usual manner for dry suction only. This serves to drain the nasal cavity of any remaining liquid, thereby obviating the desire to blow the nose violently and forcing liquid and infectious substances into the Eustachian tubes, often with serious consequences. It is, of course, appreciated that different structural features may enter into the device, such for instance as instead of using the bottle B, the bulb M could be directly connected to the nozzle head J' to take the place of the bottle B, and other changes in detail may also be resorted to without departing from the spirit of the invention, as pointed out in the subjoined claims.

I claim:

1. A nasal douche comprising a pair of receptacles, means adapted to be fitted in the nostrils of the nose so as to place the receptacles in open communication with each other, and means manually actuated for causing liquid in one of said receptacles to flow therefrom into one nostril, through the nose and out from the other nostril into the other of said receptacles and for periodically controlling said means to cause evacuation of one receptacle and a filling of the other of said receptacles and a continuous cycling of the liquid through both nostrils, first in one direction and then another.

2. A nasal douche comprising a pair of normally sealed receptacles, means adapted to fit in the nostrils of the nose so as to place said receptacles in communication with each other, and means for causing a regulated flow of liquid to pass by induced pressure from one receptacle to the other of said receptacles and to return from the latter to the former by induced pressure.

3. A nasal douche comprising means embodying a battery of reservoirs successively operable from a point beneath the nose of patient to cause an evacuation of medicated liquid from one reservoir to flow upward into one nostril, through the nose and out of the other nostril and into the other reservoir, and vice-versa, and embodying means adapted to be fitted in the respective nostrils of the nose and means for controlling conditions of the respective reservoirs to pneumatically permit said reservoirs to function as aforesaid.

4. A nasal douche comprising means embodying a battery of reservoirs successively operable from a point beneath the nose of patient to cause an evacuation of medicated liquid from one reservoir to flow upward

- into one nostril, through the nose and out of the other nostril and into the other reservoir, and vice-versa, and embodying means adapted to be fitted in the respective nostrils of the nose and means for controlling conditions of the respective reservoirs to pneumatically permit said reservoirs to function as aforesaid and means for venting the reservoirs to the atmosphere.
- 5 10. 5. In a nasal douche a pair of receptacles with open communication with each other through a patient's nasal cavity from one nostril to the other with means in connection with one receptacle for initiating a flow of liquid upwardly from the other receptacle into one nostril and drawing it through the nasal cavity and discharging it through the other nostril into the first named receptacle, and of sending the liquid back through the same passage by which it came through the nasal cavity into the receptacle which first contained it, and means for regulating the volume of liquid within the nasal cavity.
- 15 20. 6. In a nasal douche of the class described, a pair of receptacles, a separate connection between each receptacle and a patient's nostril for putting the receptacles into a reciprocative operating communication, and an independent suction apparatus in connection with one of the receptacles.
- 25 30. 7. In a nasal douche a pair of receptacles, a tube extending upward from each receptacle connecting with a patient's nostril, an open communication between said receptacles through the nasal cavity, and a means of sending a liquid supply through the nose from either receptacle to the other.
- 35 40. 8. In a nasal douche, a container for holding a liquid supply, a tube extending downwardly from the upper part of said container into its interior, a nozzle upon said container with its bore in operative communication with said tube and adapted
- 45 to fit into a nostril of a patient's nose, an air port arranged to be above the upper surface of said liquid supply; another container with a tube extending downwardly from its upper part into its interior, with a
- 50 nozzle upon said second named container with its bore in operative communication with said tube and adapted to fit into the other nostril of a patient's nose, and a hollow, elastic bulb in connection with the last named container, with means of starting a flow of liquid upwardly out from said first named container into a nostril of a patient's nose and of drawing it thence through the nasal cavity into the said second container, and means of preventing and of controlling atmospheric pressure upon the upper surface of the liquid in said first named container.
- 55 60. 9. In a nasal douche, a container for holding a liquid supply, a tube extending downwardly from the upper part of said container into its interior, a nozzle upon said container with its bore in operative communication with said tube and adapted to fit into a nostril of a patient's nose, an air port arranged to be above the upper surface of said liquid supply; another container with a tube extending downwardly from its upper part into its interior, with a
- 65 70. 75. 80. 85. 90. 95. nozzle upon said second named container with its bore in operative communication with said tube and adapted to fit into the other nostril of a patient's nose, and a hollow, elastic bulb in connection with the last named container, with means of starting a flow of liquid upwardly out from said first named container into a nostril of a patient's nose and of drawing it thence through the nasal cavity into the said second container, and means of returning the liquid from the said second named container through the nasal cavity into the said first named container.
10. In a nasal douche of the class described, a pair of receptacles, a separate communication in each receptacle for connecting with a nostril of a patient's nose, a hollow, elastic bulb connected to one of the receptacles and a manually manipulated stopper controlled opening in the other receptacle.

WILLIAM P. SPRAGUE.
